C. M. RUSHING

LIQUID FUEL BURNER

Filed May 2, 1922

Inventor

Clyde M. Rushing

Grace G. Mandella

Attorney

UNITED STATES PATENT OFFICE.

CLYDE M. RUSHING, OF BOZEMAN, MONTANA.

LIQUID-FUEL BURNER.

Application filed May 2, 1922. Serial No. 557,883.

To all whom it may concern:

Be it known that I, CLYDE M. RUSHING, a citizen of the United States, residing at Bozeman, in the county of Gallatin, State 5 of Montana, have invented certain new and useful Improvements in Liquid-Fuel Burners; and I do hereby declare the following to be a full, clear, and exact description of the invention, such as will enable others 10 skilled in the art to which it appertains to make and use the same.

This invention relates to new and useful improvements in burners and particularly to burners for vaporizing and burning 15 liquid fuel, such as kerosene.

One object of the invention is to provide a burner which has novel and improved means for supplying air, for combustion, to the escaping gas, and at the same time to 20 direct the air and gas against the generator pipes.

Another object is to provide a device of this character wherein the heat from the flame of the burning fuel is absorbed by a 25 porous material which is so arranged as to radiate its heat with the maximum efficiency.

Other objects and advantages will be apparent from the following description when 30 taken in connection with the accompanying drawing.

In the drawing:

Figure 1 is a side elevation of a burner made in accordance with the invention.

Figure 2 is a top plan view of the same.

Figure 3 is a vertical transverse sectional view on the line 3—3 of Figure 2, showing the gas openings, and the air openings with their directing wings.

Referring particularly to the accompanying drawing, 10 represents a pan having its bottom upwardly arched, throughout its length, as shown at 11, and secured to the lower face of said bottom are the transverse 45 bars 12, which are adapted to rest on the bars of a cook-stove grate, the bars being riveted to the bottom of the pan 10. Extending longitudinally of the pan, and resting in notches 13, in the upper edges of the ends 50 of the pan, are the side pipe portions 14, of the generator 15, the ends of the pipe portions being connected by the transverse pipes 16 and 17, respectively, whereby a rec-

tangular frame is thus formed. Connected to the pipe 16, in the lower side thereof, and 55 extending longitudinally in parallel relation to the pipes 14, but beneath the arched bottom of the pan, is the burner pipe 18, the other end of said pipe terminating adjacent the other transverse pipe 17, as clearly 60 seen in the plan view, Figure 2. Connected to the outer side of the pipe 17 is a liquid fuel conductor 19, which conveys fuel to the generator, and leads from any suitable 65 source, not shown.

In the pipe 18, adjacent each end, and above a horizontal line drawn through the pipe, are the gas outlet or burner openings 20, said openings being formed by boring, 70 from the outer face of the pipe to a distance approximately three-quarters of the thickness of the pipe, and then drilling a very small hole 20' in the center of the bottom of the thus bored recess or opening 20. It will be noted that these openings are 75 disposed in such position that the flame which issues therefrom, is directed against the side pipe 14. In the side walls of the arched bottom, above each of the openings 20, there is formed an opening 21, the upper and 80 lower portions of the walls thereof being bent outwardly and upwardly toward the side pipes 14, so that the gas from the openings 20 will pass therethrough, while the air from beneath the pan, will also pass upwardly through said openings, and mix with the gas, to aid the combustion thereof.

Disposed transversely of the generator, and having their downwardly curved ends 85 22', resting on the side pipes 14, are the fire-bars 22, the said bars supporting the fire-brick 23 thereon. Between the side walls 24, of the fire-pot 25, and the sides of the fire-brick 23, broken fire-brick pieces 26.

The flames from the openings 20 rise 95 against the side pipes 14, heating said pipes so as to cause the vaporization of the liquid fuel which passes through them, on the way to the burner pipe 18, and travels or rises 100 upwardly to heat the fire-brick 23, as well as the broken fire-brick 26. The heat absorbed by these bricks, and then radiated therefrom, serves to produce a sufficiently high temperature to permit heating of water 105 in the water tank and cooking or baking in the oven, as well as cooking on the top of

the stove. When the bricks have become heated to a high temperature, the flow of liquid fuel can be checked, with the consequent saving of fuel.

5 5. What is claimed is:

1. A heating device including a pan, an arch in the pan formed with openings in the sides thereof, outwardly extending air and gas directing wings in the openings, a 10 generator above the arch, a burner disposed beneath the arch and having openings positioned to discharge flame through the air openings, and heat absorbing means supported on the generator.
- 15 2. A heating device including a pan having a transversely arched bottom formed with openings in the sides thereof, outwardly extending air and gas directing wings in the openings, a generator supported on the 20 pan above the arched bottom, a burner disposed beneath the arched bottom and hav-

ing openings positioned to discharge flame through the air openings, and heat absorbing and radiating means supported on the generator.

3. A heating device including a pan, a generator supported on the pan, a burner beneath the pan, the pan having air and gas openings, means for supporting the pan on a stove grate, transverse bars on the generator, a heat absorbing and radiating member supported on the bars, and broken heat absorbing and radiating means at the sides of the first heat adsorbing and radiating means.

In testimony whereof, I affix my signature, in the presence of two witnesses.

CLYDE M. RUSHING.

Witnesses:

LEONARD S. NIEMI,
RUDOLPH K. HARTIG.
